UNITED STATES PATENT OFFICE

CLARENCE O. WENNING, OF INDIANAPOLIS, INDIANA

MARKING MACHINE

Application filed July 7, 1930. Serial No. 466,320.

This invention relates to a machine designed primarily for placing lines on the surfaces of streets and walks of all kinds for the purpose of directing traffic.

It is the practice frequently to place center lines along streets and highways, to mark off traffic lanes, safety zones, parking spaces, etc. While various kinds of apparatus have been devised for this purpose they have been generally unsatisfactory and, as a result, the use of ordinary hand brushes has been resorted to.

It is an object of the present invention to provide a machine which is simple and compact in construction for placing lines on concrete, brick, bituminous, and other surfaces whether they be rough or smooth, the said apparatus being also useful as a means for marking tennis courts and the like.

A further object is to provide a machine of this character having means whereby the paint, even though formed of readily congealing materials such as oils, coal tar products, etc., can be maintained in liquid form in the coldest temperatures.

A still further object is to provide a machine capable of using all types of marking materials whether they be such as readily congeal or whether they be of other liquids, or solids such as sand, salt, lime, chalk dust, calcium chloride, or the like.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings

Figure 1 is a plan view of the machine.

Figure 2 is a side elevation thereof.

Figure 3 is a vertical longitudinal section through the material applicator of the machine and adjacent parts, some of which are in elevation.

Figure 4 is a horizontal section through the applicator.

Referring to the figures by characters of reference, 1 designates the frame of the machine which has rear supporting wheels 2 at the sides thereof, and a single front wheel 3, the sides of the frame preferably converging forwardly as at 4 to the front wheel while adjacent to the center of the frame there are provided parallel longitudinal frame members 5 spaced apart with wheel 3 projecting between them.

The axle 6 of wheel 3 constitutes the pivot of forwardly extending side strips 7 between the front ends of which is journaled a guide wheel 8 in alinement with wheel 3.

Upwardly and rearwardly inclined handles 9 are secured to the sides of frame 1 and are suitably braced, as by means of upstanding members 10 and a cross rod 11.

Secured to the longitudinal frame members 5 are side plates 11 forming portions of the applicator. These are provided, near their front ends, with slots 12. In each of these slots is slidably mounted a stud 13 engaging the front movable section 14 of the applicator which consists of a metal plate substantially U-shaped in transverse section and having its lower front edge bent backwardly as at 15 so as to ride over any objections with which it may contact during the forward movement of the machine.

Additional side plates 16 are pivotally connected at 17 to the sides of the front section 14 and other side plates 18 are pivotally connected at 19 to the side plates 16. The rear plate 20 of the applicator has side wings 21 which are pivotally connected to the plates 18. Secured to the back plate 20 is an upwardly projecting stem 22 which works freely in a cross strip 23 connecting the frame members 5 and a spring 24 is mounted on this stem and exerts a downward pressure against the rear portion of the applicator.

If desired, cross strips 25 can connect the wings 21 and can be used for holding a transverse brush 26, the lower end of which is supported in the same plane or substantially the same plane with the lower edges of the wings 21.

It will be seen that an applicator such as described constitutes a box-like structure open at the top and bottom and having articulated side walls capable of relative movement about transverse axes. Furthermore the front end of the applicator can move upwardly and downwardly freely relative to the frame of the machine. Thus as the machine moves forwardly the applicator will slide over the surface being treated and will adapt itself to any irregularities of its contour.

For the purpose of directing marking material into the applicator there is provided a container 27 which is fixedly supported above the frame and has a downwardly tapered bottom 28 extending through a housing 29. A delivery spout 30 extends from the bottom 28 into the space within the applicator, and the lower end of this spout, normally closed by a valve 31 which is pivoted at 32 and has an arm 33 against which bears a spring 34. A flexible actuating element 35 is connected to arm 33 and extends upwardly over a guide pulley 36 and thence forwardly into engagement with another guide pulley 37. From this last pulley the connection extends to a rod 38 to which it is secured and which is slidable in guides 39 and 40 extending from one of the handles 9.

A handle 41 is provided at the upper end of rod 38 where it can be conveniently reached and actuated by the operator.

An arm 42 is pivotally connected to arm 9 and has a rod 43 extending therefrom and slidable in guide 40. An eye 44 is carried by this rod 43 and can be placed in engagement with handle 41. A spring 45 connects arm 42 to one of the upstanding members 10 so that when the eye 44 is placed in engagement with handle 41 the spring 45 will act to hold rod 38 against free movement.

The housing 29 has openings 46 over which are arranged forwardly extending hoods 47. Shelf 48 is mounted on the frame of the machine and carries heating elements which can be in the form of blow torches 49, the nozzles 50 of which extend through the openings 46.

When the marking material is of such a nature as to congeal readily during cold weather or if it requires heat to maintain it in a fluid condition, the blow torches are ignited and the flames therefrom will contact with and heat the bottom 28 of the container. As the machine is moved forwardly the wheel 8 can be used as a guide and by manipulating rod 38 the valve 31 can be opened so as to discharge a portion of the marking material into the applicator. This applicator has close contact with the surface to be marked and, consequently, the marking material will be held within bounds laterally but will be spread in the direction of travel by emerging from beneath the rear member 20. Because it is in direct contact with the surface being marked, the mass of marking material, in

the applicator will be given a circulating or rolling motion within the applicator and will tend to knead into the surface, all excess being scraped off as the material passes under the back wall of the applicator.

If the material is of a nature requiring a brush in order to properly apply it, a brush 26 can be used. If it is of a pulverulent material it will be dropped into the applicator and delivered from under the back portion thereof. Obviously the material can be delivered from the applicator as freely as desired by adjusting the stem 22 upwardly or downwardly relative to its supporting strip.

What is claimed is:

1. A marking machine including a portable structure, a box-like applicator movable therewith and relative thereto, said applicator having articulated side walls and an open bottom, and means carried by the structure for directing marking material into the applicator for rolling contact with the surface to be marked.

2. A marking machine including a movably supported structure, a box-like applicator movable therewith having articulated side walls for sliding engagement with a surface to be treated, the bottom of the applicator being adapted to be closed solely by the surface being marked, a container on the structure, and means under the control of an operator for directing marking material from the container to the applicator for rolling contact with the surface being marked.

3. A marking machine including a movably supported structure, a box-like applicator connected thereto for up and down movement relative to the structure and having articulated side walls and an open bottom, and means for directing marking fluid into the applicator for rolling contact with the surface being marked, the back wall of said applicator providing an outlet thereunder for the fluid and constituting a scraper for surplus fluid.

In testimony that I claim the foregoing as my own, I have hereto affixed my signature.

CLARENCE O. WENNING.
